FIG. 1 is an end elevational view of a bar of soap or the like showing my new design.

FIG. 2 is a top plan view of the same.

FIG. 3 is a side elevational view of the same.

FIG. 4 is a cross-sectional view taken on the line 4—4 of FIG. 2.

FIG. 5 is a perspective view of the same.

FIG. 6 is a cross-sectional view taken along the lines 6—6 of FIG. 2.

The characteristic features of my design reside in the combination on the bar of soap disclosed of the planar mid section on the upper and lower faces which merges into a full width groove at each end all as shown.

I claim:

The ornamental design for a bar of soap or the like, as shown and described.
